Patented Mar. 1, 1921.

UNITED STATES PATENT OFFICE.

RICARDO BARTOLOMÉH, OF NEW YORK, N. Y.

STOP FOR PHONOGRAHS.

1,370,266.

Specification of Letters Patent.

Patented Mar. 1, 1921.

Application filed September 8, 1920. Serial No. 408,801.

To all whom it may concern:

Be it known that I, RICARDO BARTOLOMÉH, a citizen of Venezuela, and a resident of the city of New York, borough of Manhattan, 5 in the county of New York and State of New York, have invented a new and Improved Stop for Phonographs, of which the following is a full, clear, and exact description.

10 In connection with talking machines, it is a well appreciated fact that numerous devices have been placed upon the market with a view of providing a stop which would be actuated automatically upon the 15 reproducer reaching the last groove of the record.

These devices, although positive in operation, have left much to be desired in that it has been incumbent upon the operator of 20 a machine to set the automatic stopping device so that a brake would be exerted upon the stylus of the reproducer traversing the last groove of the record, or those grooves adjacent the same.

25 This was necessary, due to the fact that each record varies with respect to the number of convolutions of the spiral groove in its face, consequently the reproducing groove in certain types of records terminates at a point but one inch removed from the outer edge of the record, while in other cases, the groove is continued to a point adjacent the edge of the label commonly placed at the center of the record.

30 35 Having this defect in mind, I have now invented a stop for phonographs which shall be entirely automatic in operation, in that it will not be necessary to insure the stoppage of the turn table upon the stylus 40 of the reproducer traversing the last portion of the groove in the face of the same.

By this construction it will readily be appreciated that an entirely automatic result will be achieved, in that it will only be 45 necessary to place the record upon the turn table, and set the latter in motion, subsequent to which the stylus of the reproducer is introduced to the initial groove upon the face of the record in the usual manner, to 50 insure the automatic stoppage upon the reproduction being completed.

Reference is had to the attached sheet of

drawings as illustrating one practical embodiment of my invention, and in which—

Figure 1 is a bottom plan view of a turn 55 table and its associated parts, constructed in accordance with my invention.

Fig. 2 is a sectional side view taken along the lines 2—2 of Fig. 1, and

Fig. 3 is a top plan view of a turn table, 60 and showing a record applied thereto in accordance with my invention.

In these views the reference numeral 5 indicates the base, which may be conventional in construction, and upon which a turn 65 table 6 is rotatably supported by means of the motor shaft 7, such turn table in turn receiving the conventional disk record 8 in sound grooves 9 of which a reproducer 10 travels.

Contrary to the conventional construction however, it will be noted that the record 8 is conveniently formed with a cut-out portion 11, which cut-out portion, as will be noted in Fig. 3, is in the form of an arc 75 of a circle having as its center the apex of the motor shaft 7.

The turn table 6 is also formed with a cut-out portion, which latter portion is adapted to be brought into alinement with the cut-out portion 11 of the record.

A plate 12 is normally supported in the cut-out portion of the turn table 6 by means of a spring actuated lever 13, associated with the under-side of the turn table 6, in which position it is pivotally supported, as has been indicated by the reference numeral 14. In this connection, it is to be noted that the plate 12 conveniently conforms to an arc similar to that of the cut-out portion 90 11 of the record 8, with the exception that the plate 12 covers a greater area than the last cut-out portion.

A braking device conveniently co-acts with the turn table 6, and upon being actuated serves to support the same. This brake preferably includes a lever 15, which is pivotally supported, as at 16, upon the base 5, it being noted that one end of a contraction spring 17 is attached to the lever 100 beyond its point of pivotal association with the base in such a manner that the lever will be retained in either of its extreme positions past dead center.

A contact member 18 conveniently forms a part of the lever 15, and such contact member is adapted to be brought to bear by means of the spring, as has been indicated 5 in dotted lines against a convenient portion of the turn table 6, whereby to cause a cessation of operation of the latter.

As has been illustrated in Fig. 2, the spring associated with the lever 13 serves to 10 normally retain the outer end of the latter in a plane at which the same will be out of the path of travel of the inner end of the lever 13. However, upon the stylus of the reproducer 10 entering the cut-out portion 15 11 of the record (as has been indicated in dotted lines in Fig. 2) and bearing against the plate 12, the lever will be depressed to the position also indicated in dotted lines in this figure, which will result in the outer 20 end of this lever being swung to a position at which, upon the next revolution of the turn table, the inner end of the lever 15 will be engaged, and the latter will be swung past dead center to the position indicated 25 in dotted lines in Fig. 1, which, as will obviously be appreciated, will serve to bring the turn table to a stop.

In this connection it will be noted that the lever 15 may be reset, by virtue of that 30 portion of the same extending beyond its point of pivotal connection, which will permit of the manual operation of this latter, as well as the re-setting of the same aforementioned.

35 Obviously numerous modifications of structure might readily be resorted to without in the least departing from the spirit of my invention, which I claim as—

1. A stop for talking machines, including 40 a turn table, a record adapted to be positioned upon said turn table, said record being formed with an opening, a reproducer adapted to traverse the sound grooves of

said record, the last sound groove of said record communicating with said cut-out portion, a brake, and means connected to said turntable for actuating said brake when the stylus of said reproducer moves into the cut-out portion of said record. 45

2. A stop for talking machines, including 50 a turn table, a record adapted to be positioned upon said turn table, said record being formed with an opening, a reproducer adapted to traverse the sound grooves of said record, the last sound groove of said record communicating with said cut-out portion, a brake, a plate movably positioned 55 with an opening forming a part of said turn table, said plate being adapted to directly underlie the cut-out portion of the record, and means connected with said plate for actuating said brake when the stylus of said reproducer moves into the cut-out portion of the record and contacts with same. 60

3. A stop for talking machines, including 65 in combination with a turn table formed with a cut-out portion, a record also formed with a cut-out portion and adapted to be placed upon said turn table, the cut-out portions both alining, a lever, a plate connected to the end of said lever, means for normally holding said lever so that the plate is normally held in position within the cut-out portion of the turn table, a brake for 70 said turn table, said brake including a lever, 75 said lever being out of the path of travel of said first named lever, the stylus of the reproducer being adapted to traverse the grooves of the record, and to move through a cut-out portion of the same, whereby to contact with said plate, and to move the end of the lever connected with the same into a plane at which it will contact with the brake lever, whereby to actuate said brake. 80

RICARDO BARTOLOMÉH.
